UNITED STATES PATENT OFFICE.

EDWIN G. WEISSMAN, OF EASTON, PENNSYLVANIA, ASSIGNOR TO INDIVIDUAL DRINKING CUP COMPANY, INC., OF EASTON, PENNSYLVANIA, A CORPORATION OF PENNSYLVANIA.

DISPENSING DEVICE.

Application filed September 12, 1924. Serial No. 737,362.

This invention relates to improvements in dispensing devices and more particularly to improved indicating means therefor, the improved indicating means being especially useful with dispensing devices of the coin or check controlled type for indicating when the apparatus is not in service as when the same does not contain any articles to be dispensed.

10 The object of the invention is to provide improved indicating means of a simple efficient nature compactly combined with the structure of the dispensing device and adapted to be easily adjusted or set to give 15 the desired indication.

A further object of the invention is to provide improved indicating means of the character referred to with means for locking the same in set position against unauthorized operation thereof.

In the drawings:

Figure 1 is a front elevation of a dispensing device equipped with indicating means in accordance with the present invention, the indicating means being shown set with its signal facing to the front of the casing in view.

Fig. 2 is a rear elevation, the indicating means being shown with its sign facing to the rear of the casing.

Fig. 3 is a side elevation, the indicating means being shown with its sign facing to the rear of the casing.

Fig. 4 is a vertical section on the line 4—4 of Figure 5.

Fig. 5 is a horizontal section on the line 5—5 of Figure 4.

Fig. 6 is a detail side elevation of the container.

Fig. 7 is a bottom plan view of the container.

The invention comprehends a dispensing device including a supporting casing having a socket part, a container adapted to be detachably seat in said socket part, and a ring like part bearing thereupon a sign, said part being adjustable circumferentially relatively to the casing to position the same with its sign facing to the front of the casing in view, or to position the same out of said position at another point about the casing out of view. The invention further contemplates means for positioning and hold-

ing the ring like sign bearing part in its different positions of adjustment against rotary movement relatively to the casing, and means for locking the same against unauthorized operation.

In the drawings, the invention is shown in connection with one of the well known accepted forms of devices for vending paper cups comprising a metal casing 1 adapted to be secured to any suitable support and forming a support for a glass container tube 2 and coin controlled mechanism (not shown) for delivering cups singly from a stack of nested cups within the container to the delivery opening 3 of the casing 1, the casing having a cylindrical socket part 4 extending upwardly from the top thereof in which the container tube 2 is detachably seated. The cup delivery mechanism, located within the casing 1, includes an oscillating feed member 5 having an operating handle 5' projecting through a slot in the casing. 7 designates the slot in the casing to receive the coin or check.

Referring to a detail description of the particular embodiment of the invention illustrated in the drawings, the glass container tube 2 is provided at its lower end with a metal collar or thimble having an upper socket part 8 extending over the lower end of the glass container tube 2, and a lower section 9 of less diameter than the socket part 8 adapted to fit into the socket part 4 of the casing 1, said lower section 9 of the collar or thimble being disposed in alignment with and forming a continuation of the glass container tube 2. The collar or thimble is fixedly secured on the glass container tube 2 by plaster of Paris 10 or other suitable cementitious material. The container is provided on the outer face of the socket part 8 of its collar or thimble with letters forming a sign 11, the sign extending over a restricted area of the outer face of the socket part 8 of the collar or thimble, the container being adapted to be seated in the socket part 4 of the casing 1 with the sign 11 facing to the front of the casing 1 in view, or to be arranged with its sign out of said position at a different point about the casing out of view, the upper socket part 8 of the metal collar or thimble affording an opaque section so that when the

container is positioned with its sign out of front position, for instance, facing to the rear of the casing, the sign will be completely out of view. In the present instance the sign is shown consisting of the words "Not in service" to indicate when the dispensing device is not in service as when the same does not contain any articles to be dispensed.

The lower section 9 of the collar or thimble of the cup container and the socket 4 of the casing 1 are constructed to provide for readily positioning and for holding the collar or thimble in its different positions of adjustment relatively to the casing 1 with its sign facing to the front of the casing in view, and with its sign facing to the rear of the casing out of view. In the particular construction shown the lower section 9 of the collar or thimble and the socket part 4 of the casing 1 are of cylindrical form and provided with portions adapted to interfit with each other to position and hold the collar or thimble in its adjusted positions against rotary movement relatively to the socket part 4 of the casing. For this purpose, the collar or thimble is provided on its lower section 9 with a pair of lugs 12 adapted to cooperate with a pair of recesses 13 on the socket part 4 of the casing, the pair of lugs 12 on the collar or thimble being disposed diametrically opposite in a line extending centrally of the sign 11 on the upper socket part 8 of the collar or thimble and the recesses 13 being diametrically oppositely disposed in a line extending centrally of the casing 1 from front to rear. The recesses 13 in the particular construction shown in the drawings take the form of tubular lateral extensions of the socket part 4 of the casing. As will be understood the sign 11 on the collar or thimble of the container may be readily adjusted or arranged to face to the front of the casing 1 in view or to face to the rear of the casing out of view, by withdrawing the container out of the socket part 4 of the casing, and inserting the same in the socket part 4 with the positions of the lugs 12 reversed, the lugs 12 and recesses 13 assisting in arranging the container in proper position relatively to the socket part 4 and positively defining the location of the sign to face directly to the front or to the rear of the casing.

Means is provided for locking the container to the casing 1 and for locking the indicating means in its different positions, said means comprising a latch member 15 adapted to engage the lugs 12 on the lower section 9 of the collar or thimble of the container. Each of the lugs 12 is provided with a recess 16 intermediate its ends, the recess 16 having a flat bottom wall 16'. The latch member 15, in the particular exemplification of the invention shown, consists of

a relatively short rotatable shaft, semicircular in cross section, having a flat face 15' to engage over the bottom wall 16' of the recesses 16 of the lugs 12. The casing 1 is provided with a tubular boss or extension 17 adjoining the socket part 4 providing a cylindrical chamber 18 to receive a lock 19, and a smaller cylindrical chamber 20 for the latch member 15, the last mentioned chamber extending transversely of and communicating with the recess 13 on the socket part 4 located at the rear side of the casing, the rotatable latch member 15 being fixed to the shaft 21 of the lock 19 to be operated thereby to engage over the bottom wall 16' of the recesses 16 of the lugs 13, or turned back into the chamber 20 out of engagement with the lugs 13, as indicated respectively in full and dotted lines in Figure 4 of the drawings. The lock 19 may be of any suitable construction, that shown being one of the conventional forms of key operated permutation cylinder locks, the lock being secured in the chamber 18 by any suitable means.

It will be noted that the special construction and arrangement of parts hereinbefore set forth affords indicating means of a simple efficient nature that can be quickly and easily set or positioned as desired, the indicating means being compactly arranged with the structure of the dispensing apparatus, and provision being made to prevent the unauthorized operation of the same.

While a specific embodiment of the invention is illustrated in the drawings, it will of course be understood that changes and variations in the particular construction shown may be made, and the invention embodied in other forms, as will appeal to those skilled in the art and falling within the scope of the appended claims, without departing from the spirit of the invention. Different kinds of signs for different purposes may be employed and the invention may be used in connection with dispensing devices of various types and for dispensing various kinds of articles.

What I claim is:

1. In a dispensing device, a supporting casing including a socket part, a container adapted to detachably seat in said socket part, the container having a ring like part thereon bearing thereupon a sign, said part being adjustable relatively to the casing to position the same with its sign facing to the front of the casing in view, or to position the same out of said position at another point about the casing out of view, and stop means for holding said ring like part in either of said positions against rotary movement relatively to the casing.

2. In a dispensing device, a supporting casing including a socket part, a container adapted to detachably seat in said socket

- part, the container having a ring like part thereon bearing thereupon a sign, said part being adjustable relatively to the casing to position the same with its sign facing to the 5 front of the casing in view, or to position the same out of said position at a different position about the casing out of view, and means on said part and said socket part adapted to interfit one with the other to hold said part 10 in its different positions of adjustment against rotary movement relatively to the casing.
3. In a dispensing device, a supporting casing including a socket part, a container 15 adapted to detachably seat in said socket part, the container having a ring like part thereon bearing thereupon a sign, said ring like part being adjustable relatively to the casing to position the same to the front of 20 the casing in view, or to position the same out of said position at a different point about the casing out of view, and key operated means for locking said part in either of said 25 positions.
4. In a dispensing device, a supporting casing including a socket part, a container adapted to detachably seat in said socket part, the container having a sign fixed thereto and adapted to be positioned in said 30 socket part with its sign facing to the front of the casing in view or positioned with said sign out of said position at a different point about the casing out of view, said socket part and said container having interfitting parts whereby the container is held 35 from rotation when seated in said socket part in either of said positions.
5. In a dispensing device, a supporting casing including a socket part, a container 40 adapted to detachably seat in said socket part, the container bearing thereupon a sign and adapted to be positioned with its sign facing to the front of the casing in view or positioned with its sign facing toward the 45 rear of the casing out of view, and stop means for holding the container in either of said positions against rotation relatively to the casing.
6. In a dispensing device, a supporting 50 casing including a socket part, a container adapted to detachably seat in said socket part, the container bearing thereupon a sign and adapted to be positioned with its sign facing to the front of the casing in view or 55 positioned with its sign out of said position disposed at a different point about the casing, and key operated means for locking the container to the casing against longitudinal movement relative to the casing.
7. In a dispensing device, a supporting 60 casing including a cylindrical socket part having a pair of recesses disposed diametrically opposite in a line extending centrally of the casing from front to rear, a 65 container having a lower cylindrical part adapted to detachably seat in said socket part and provided with a pair of diametrically oppositely disposed lugs to engage the recesses of the socket part, the container bearing thereupon a sign arranged in vertical alignment with one of said lugs, said container being adapted to be seated in said socket with its sign facing to the front of the casing in view or to be positioned with its sign facing toward the rear of the casing out of view.
8. In a dispensing device, a supporting casing including a cylindrical socket part having a pair of recesses disposed diametrically opposite in a line extending centrally of the casing from front to rear, a 70 container having a lower cylindrical part adapted to detachably seat in said socket and provided with a pair of diametrically oppositely disposed lugs to engage the recesses of the socket part, the container bearing thereupon a sign arranged in vertical alignment with one of said lugs, said container being adapted to be seated in said socket with its sign facing to the front of the casing in view or to be positioned with its sign facing toward the rear of the casing out of view.
9. In a dispensing device, a supporting casing including a cylindrical socket part having a pair of recesses disposed diametrically opposite in a line extending centrally of the casing from front to rear, a container having a lower cylindrical part adapted to detachably seat in said socket and provided with a pair of diametrically oppositely disposed lugs to engage the recesses of the socket part, the container bearing thereupon a sign arranged in vertical alignment with one of said lugs, said container being adapted to be seated in said socket with its sign facing to the front of the casing in view or to be positioned with its sign facing toward the rear of the casing out of view, and key operated means for locking the container to the casing in either of said positions, said key operated means 90 including a latch member adapted to interlock with said lugs.
10. In a dispensing device, a supporting casing including a cylindrical socket part having a pair of recesses disposed diametrically opposite in a line extending centrally of the casing from front to rear, a container having a lower cylindrical part adapted to be detachably seated in said socket and provided with a pair of diametrically oppositely disposed lugs to engage the recesses of the socket part, the container bearing thereupon a sign arranged on a portion thereof in vertical alignment with one of said lugs, said container being adapted to be seated in said socket with its sign facing to the front of the casing in view or to be positioned with its sign facing toward the rear of the casing, each of said lugs being provided with a notched part, and key operated means for locking the container to the casing in either of said positions, said last mentioned means including a latch member adapted to engage the notched portions of the lugs.
11. In a dispensing device, a supporting casing including a socket part, a glass container tube adapted to be detachably seated in said socket part, the container tube having a lower opaque part having printed upon a restricted area thereof a sign, the container being adapted to be positioned with its sign facing to the front of the casing in view or positioned with its sign disposed out of said position at a different point about 120
12. In a dispensing device, a supporting casing including a socket part, a glass container tube adapted to be detachably seated in said socket part, the container tube having a lower opaque part having printed upon a restricted area thereof a sign, the container being adapted to be positioned with its sign facing to the front of the casing in view or positioned with its sign disposed out of said position at a different point about 130

the casing, and means for holding the container in either of said positions against rotary movement relatively to the casing.

11. In a dispensing device, a supporting casing including a socket part, a container adapted to detachably seat in said socket part, the container bearing thereupon a sign and adapted to be positioned with its sign facing to the front of the casing in view or positioned with its sign out of said position disposed at a different point about the casing, said socket part and said container being constructed to interfit one with the other whereby the container is held from rotation when seated in the socket part in either of said positions, and means for locking the container to said socket in either of said positions.

12. In a dispensing device, the combination with a supporting casing including a socket part, a container having a lower part adapted to detachably seat in said socket part, of a ring like member bearing a sign thereupon, said ring like member being associated with said socket part for rotary adjustment relatively thereto to position the same with its sign facing to the front of the casing in view or to position the same with its sign out of said position disposed at a different point about the casing out of view, and stop means for holding the ring like member in its different positions of adjustment against rotary movement relatively to the casing.

13. In a dispensing device, the combination with a supporting casing including a socket part, a container having a lower part adapted to detachably seat in said socket part, of a ring like member bearing a sign thereupon, said ring like member being associated with said socket part for rotary adjustment relatively thereto to position the same with its sign facing to the front of the casing in view or to position the same with its sign out of said position disposed at a different point about the casing out of view, means for holding the ring like member in its different positions of adjustment against rotary movement relatively to the casing, and means for locking the ring like member to the casing in its different positions of adjustment.

14. In a dispensing device, the combination with a supporting casing including a socket part, a container having a lower part adapted to detachably seat in said socket part, of a ring like member bearing a sign thereupon, said ring like member being as-

sociated with said socket part for adjustment circumferentially of its own axis thereabout to position the same with its sign facing to the front of the casing in view or to position the same with its sign out of said position disposed at a different point about the casing out of view, and means for locking the ring like member in its different positions of adjustment to the casing.

15. In a dispensing device, the combination with a casing, of a band like member bearing a sign thereupon, said band like member being associated with a part of the casing for adjustment circumferentially of its own axis thereabout to position the same thereon with its sign facing to the front of the casing in view or to position the same with its sign out of said position disposed at a different point about the casing, said band like member and the casing having parts adapted to interfit one with the other for positioning and holding the band like member in its different positions of adjustment about the casing.

16. A dispensing device comprising a casing member and a container operatively associated therewith, said device including a ring like member bearing a sign, said ring like member being associated with the casing member and container for adjustment circumferentially of its own axis thereabout to position the same with its sign exposed at the front or hidden from the front, and stop means for maintaining the ring like member in either position of its adjustment.

17. In a dispensing device, a supporting casing including a cylindrical socket part, a container having a lower cylindrical part adapted to detachably seat in the socket part of the container, said container bearing thereupon a sign and being adapted to be seated in said socket part with its sign facing to the front of the casing in view or at a different point about the casing out of view, said socket part having a pair of recesses disposed diametrically opposite in a line extending centrally of the socket from front to rear, and said lower cylindrical part of the container having a lug arranged in vertical alignment with said sign and adapted to be engaged with either of the recesses to position and hold the container in either of said positions against rotary movement relatively to the casing.

In testimony whereof I hereunto affix my signature.

EDWIN G. WESSMAN.
